UNITED STATES PATENT OFFICE.

JOSIAH PARTRIDGE, OF NEW YORK, N. Y.

DESIGN FOR CHAIRS.

Specification forming part of Design No. **11,551**, dated December 23, 1879; application filed October 20, 1879.
[Term of patent 7 years.]

To all whom it may concern:

Be it known that I, JOSIAH PARTRIDGE, of the city, county, and State of New York, have originated and designed a Chair, of which the following is a full, clear, and exact description, reference being had to the accompanying drawing, making part of this specification.

A represents the back posts of the chair, which posts are curved and recurved, as at *a* and *b*. The front edges or faces of these posts are ornamented by moldings *c*. Connecting these back posts near their upper end is a head-piece, *B*, composed substantially of an open continuous frame, with the inclosed space *d* crossed vertically by ornamental posts *e*, and with balls *f* fixed to the upper edge of the frame coincident with the ornamental posts before referred to, the whole head-piece forming the design of a coronet. Near the seat *C*, and extending from one back post, *A*, to another, is a plain curved bar, *D*. Extending from this last-mentioned bar to the head-piece *B*, centrally, is a polygonal piece, *E*, with an ornamental opening, *g*, formed therein. The frame of the seat *C*, which is circular, or nearly so, around its edge, is ornamented by a molding, *h*, extending around the front and sides of the seat-frame from back post to back post, and

from the under side of this seat-frame depends an ornamented cleat, *i*, of the design shown in the drawing. The front legs, *G*, are straight and cylindrical in form and ornamentally turned. The back legs, *H*, are rectangular in section, and connected to the front legs by cylindrical braces *k*, the front legs being united to each other by ornamentally-turned braces *l*.

What I claim as my invention is—

A design for a chair in which the back posts, *A*, and seat-frame *C* are ornamented by moldings, the moldings on the seat-frame extending around the front and sides of the same to the back posts, and having the head-piece of the design of an entire frame, *B*, with the space between the sides of the frame ornamented by spindles *e* and the top edge of the frame by balls *f*, and with a polygonally-shaped piece, *E*, in part filling the space inclosed by the back posts, *A*, the head-piece *B*, and the plain outlined and curved bar *D*, the seat-frame being also ornamented by a cleat, *i*, with irregularly-cut edge, substantially in the manner described.

JOSIAH PARTRIDGE.
